(57) **CLAIM**

The ornamental design for an outlet plate, as shown and described.

DESCRIPTION

FIG. 1 is a perspective view of an outlet plate showing our new design;

FIG. 2 is a first end view thereof, the opposite end being a mirror image of the end shown;

FIG. 3 is a front elevational view thereof; and,

FIG. 4 is a first side view thereof, the opposite side being a mirror image of the side shown.

The broken lines shown in FIGS. 1 and 3 is included for the purpose of illustrating portions of the outlet plate and forms no part of the claimed design.

1 Claim, 2 Drawing Sheets
